UNITED STATES PATENT OFFICE

113,323

DESIGN FOR A PRESSURE GAUGE

Willard R. Campbell, Long Beach, Calif.

Application February 21, 1938, Serial No. 75,310

Term of patent 3½ years

To all whom it may concern:

Be it known that I, Willard R. Campbell, a citizen of the United States, residing at 113-A Rivo Alto Canal, City of Long Beach, county of Los Angeles and State of California, have invented a new, original, and ornamental Design for a Pressure Gauge, of which the following is a specification, reference being had to the accompanying drawing, form a part thereof.

Figure 1 is a front elevation of the gauge.

Figure 2 is a side elevation of the same.

I claim:

The ornamental design for a pressure gauge, as shown.

WILLARD R. CAMPBELL.
